UNITED STATES PATENT OFFICE.

WILLIAM L. SMITH, OF TUSCUMBIA, ALABAMA.

VALVE-GEAR.

1,249,534.

Specification of Letters Patent. Patented Dec. 11, 1917.

Application filed February 20, 1914. Serial No. 820,012.

To all whom it may concern:

Be it known that I, WILLIAM L. SMITH, a citizen of the United States, residing at Tuscumbia, in the county of Colbert and State 5 of Alabama, have invented certain new and useful Improvements in Valve-Gears; and I do hereby declare the following to be a full, clear, and exact description of the invention, such as will enable others skilled in the art 10 to which it appertains to make and use the same.

My invention relates to certain new and useful improvements in valve gear for locomotives and other reversing engines and resides 15 in the provision of simple and efficient gearing of the radial type that is capable of being readily attached to locomotives and will operate to prevent irregularity of valve action and insure quick closing and opening 20 of the valve.

An important object of my invention is to provide valve gear of the character described which is extremely simple as to construction and dispenses with the expensive 25 and troublesome link generally employed in valve gear for locomotives and other reversing engines.

A further important object of my invention is to provide a valve gear of the character 30 described which may be readily attached to different styles of locomotives and reversing engines without necessitating any material change in the construction of the engine to which it is to be attached, said 35 attachment being permitted readily and easily.

Another important object of my invention is to provide a novel form of frame for supporting the main elements of the gearing, 40 said frame being readily attachable to different styles of locomotives and light and strong, also enabling the efficient operation of the gearing and supporting the gearing in such a way that little attention or repair 45 is required to maintain the gearing in operation.

A further important object of my invention is to provide gearing of the character described which is simple as to construction 50 capable of being readily assembled and disassembled and cheap to install.

The above and additional objects are ac-

complished by such means as are illustrated in the accompanying drawings, described in the following specification and then more 55 particularly pointed out as claimed.

With reference to the drawings, wherein I have illustrated the preferred embodiment of my invention as it is reduced to practice, and throughout the several views of which 60 similar reference numerals designate corresponding parts:

Figure 1 is a side elevation showing my improved valve gear attached to a locomotive. 65

Fig. 2 is an inside elevation of the valve gear showing portions of the locomotive in dotted lines, and

Fig. 3 is a fragmentary top plan view of the valve gear showing a portion of a locomotive. 70

Fig. 4 is a transverse sectional view taken substantially on the line 4—4 of Fig. 1.

Referring to the drawings, 1 designates the cylinder, 2 the valve chest having a valve 75 therein not shown, and 3 the usual valve stem or rod. The usual cross head 4 connects the piston rod with the usual drive rod 5.

On the main crank 6, is rigidly mounted 80 an auxiliary crank 7. To auxiliary crank is coupled one end of an eccentric rod 8.

Suitably mounted upon the locomotive is a frame 9 which consists of transverse bars 10 and 11 that are suitably secured at their 85 ends to connecting plates 12. A downwardly extending vertical plate or bar 13 is formed integral with the plates 12 at points approximately centrally of the ends of the plates and angular brace bars 14 are 90 joined integrally at their ends to the end edges of the plates 12 and lower end of the plates or bars 13. The bars 14 extend downwardly in a convergent plane with respect to the plates 12. The transverse bars 10 and 11 are recessed centrally of their ends or 95 cut away so as to fit the boiler of the locomotive.

The frame 9 is secured by bolts or other suitable fastening means transversely of the 100 lower frame of the locomotive. The connecting plates 12 and plates 13 and bars 14 are disposed upon the sides of the locomotive adjacent to the valve and steam chest.

Secured in any suitable manner upon the inner face of the side bar 10 of the frame adjacent to one end thereof is a U-shaped bracket 15. The bracket 15 is preferably secured by a bolt or bolts 16 and is removable with relation to the frame. A bell crank 17 is journaled as at 18 within the bracket 15, is connected pivotally at one end with the outer end of the valve rod or stem 3 as at 19 and 5 at its other end as at 20 is pivotally connected one end of a substantially upright link 21. The link 21 is connected at its other or lower end as at 22 with the eccentric rod 8 at the end of the eccentric rod. The ends 10 of the link 21 are preferably bifurcated to receive the ends of the bell crank 17 and eccentric rod 8. The eccentric rod 8 and link 21 are upon the inside of the plates 12 and 13 and bars 14 of the frame 9. Mounted in 15 bearing brackets 23 that are suitably secured to the side bar 11 of the frame 9 and extend outwardly at right angles thereto is a tumbling shaft designated 24 as an entirety. This shaft 24 extends outwardly from the 20 locomotive and terminates at a point approximately flush with the plates 12 of the frame. A reach rod 25 is operatively connected as at 26 to an arm 24^a of the tumbling shaft 24 at a point spaced from the ends of 25 the tumbling shaft preferably and at its other end is connected with the usual reversing lever 27 that is carried in the cab of the locomotive. An auxiliary reach rod 28 is connected at its ends as at 29 and 30 30 respectively with the end of an arm 29^a of the tumbling shaft 24 and an apertured extension 31 that is formed on the end of a tumbling reverse yoke 32. The tumbling yoke 32 is approximately U-shaped and straddles 35 the plates 12 on the frame 9. The lower ends 40 of the sides of the yoke are pivoted as at 33 to the frame 9 at that point where the bars 14 are joined with the plate 13 as clearly 45 shown in Fig. 1 in the drawings. The plates 12 and 13 serve to support and properly 50 guide the tumbling yoke 32. The arms of the yoke are arranged upon opposite sides of the plates 12 and 13. A connecting pin 34 is carried by the inner side of the yoke 32 55 adjacent to the upper end thereof.

A radius bar or link 35 is pivotally connected as at 36 with the eccentric rod 8 at a point adjacent but slightly spaced from the connections 22 designating the connection 60 of the upright link 21 and bar 8. The radius bar or link 35 is approximately upright and connected at its upper end pivotally with the connecting pin 34 as clearly shown in Figs. 2 and 3 in the drawings.

65 The radius bar 35 is supported by the tumbling yoke 32 and it will be readily seen that upon the manipulation of the lever 27, the tumbling yoke 32 will be moved in an arc

and in so moving moves the radius bar or link in such a way that the eccentric rod 8 65 is caused to change its position and the reversing of the valve is resultant.

It will be readily seen with reference to the foregoing description and accompanying drawings that I have provided simple and 70 inexpensive valve gearing which entirely dispenses with the extremely troublesome and expensive link generally employed in valve gearing and operates to bring about a quick opening and closing of the valve and 75 to dispense with all irregularity of valve motion due to lost motion or "pounding" at the crank.

It is to be noted that my valve gearing may be readily attached to locomotives in 80 a most expeditious manner without necessitating any material change in the construction of the locomotive or requiring much time or labor.

In practice, I have found that the form of 85 my invention, illustrated in the drawings and referred to in the above description, as the preferred embodiment, is the most efficient and practical; yet realizing that the conditions concurrent with the adoption of 90 my device will necessarily vary, I desire to emphasize the fact that various minor changes in details of construction, proportion, and arrangement of parts may be resorted to, when required, without sacrificing 95 any of the advantages of my invention, as set forth.

What is claimed is:—

A valve gear including a transverse frame comprising front and rear transverse bars 100 and a side plate connecting the transverse bars and provided with a depending portion having a lower terminal located centrally between the ends of the side plate, a reverse yoke having spaced sides and straddling the 105 side plate and pivoted at the lower ends of its sides to the lower end of the said depending portion of the side plate, said yoke being provided at its upper end at its inner side with a horizontal connecting pin and 110 having a longitudinal extension projecting above the pin, a radius link located within the frame at the inner face of the side plate and pivoted at its upper end to the reverse yoke by the said pin, an eccentric rod connected to the lower end of the radius link and located within the frame and extending in advance of the said radius link, front and rear bearing brackets secured to the transverse bars of the said frame, a bell crank 115 mounted in the front bearing bracket in the transverse frame, an upright link located in advance of the said yoke and connected with the bell crank lever and to the front end of the eccentric rod and operating within 120 the said transverse frame, a valve rod ac-

tuated by the bell crank, a rock shaft journaled in the rear bearing bracket, an auxiliary reach rod connected at its front end to the extension of the reverse yoke and connected at its rear end to the rock shaft, and a reversing lever also connected with the rock shaft.

In testimony whereof I affix my signature in presence of two witnesses.

WILLIAM L. SMITH.
